UNITED STATES PATENT OFFICE.

JOHN R. CONNOR, OF FRANKLIN, PENNSYLVANIA.

RIVETING-MACHINE.

SPECIFICATION forming part of Letters Patent No. 287,630, dated October 20, 1883.

Application filed February 10, 1883. (No model.)

To all whom it may concern:

Be it known that I, JOHN R. CONNOR, of Franklin, in the county of Venango and State of Pennsylvania, have invented a new and useful Improvement in Sheet-Metal-Riveting Machines, of which the following is a full, clear, and exact description, reference being had to the annexed drawings, forming a part of this specification.

10 This invention relates to machines for inserting and heading rivets in sheet-metal by a continuous and partially automatic operation; and the invention consists of the novel construction hereinafter described and claimed.

15 In the drawings, Figure 1 is a perspective view of my riveting-machine. Fig. 2 is a horizontal section of the rivet-heading arm. Fig. 3 is a vertical section through the hammer-carrying shaft. Fig. 4 is a front view, partly 20 in section, and Figs. 5 and 6 are modifications, of the rivet-heading arm.

A indicates the base-frame of the machine, having perforations *a*, by which it may be secured to the end of a suitable bench or table. 25 In the ends B B of the frame A is centered a shaft, C, to which the hammer D is secured by collar or holder, E, and a set-screw, F. This shaft is also provided with a drum, G, and retracting-springs H, for winding the 30 strap I on the drum, and lifting the hammer. The strap, which is to pass down through an opening in the table, is to be provided with a stirrup, whereby foot-power may be applied to the hammer. I design, also, to adapt the machine to be run by motor-power.

35 At the front of the base-frame A is an anvil, J, in the upper surface of which one or more recesses, K, are to be formed for holding the rivets during the operation of inserting and heading the same. It is designed that a portion of the upper surface of the anvil shall be plated with steel, to provide suitable resistance to the blows of the hammer, and in such case the recesses K will be formed in the 40 surface of the steel plate. At right angles to the anvil, and arranged slightly above the same, is the rivet-heading arm L. This arm consists of the sliding bar M, supported in the sleeve N on the end of the oscillatory rod O, which rests in the bracket P on the front of the frame A, at one side of the anvil. The 45 sliding bar M is provided with a coil-spring,

Q, against the tension of which it is to be moved longitudinally by a lever, R, which is pivoted to the upper surface of the frame A, 55 and is adapted to be oscillated by a cam, S, on the shaft C. The object of the longitudinal movement of the bar M will be hereinafter explained. The extreme end of the bar M is provided with a perforation, T, which is to 60 register with one of the recesses K when the rivet is placed in the latter preparatory to being inserted into the sheet of metal. A blow of the hammer on the bar M causes the latter to descend on the anvil by an oscillation of 65 the rod O against the tension of a coil-spring, U, and the upper end of the rivet, as it penetrates the metal, is received into the perforation T. As the hammer is lifted for the second blow, by which the upper end of the rivet is 70 to be headed, the bar M returns to its normal position above the rivet, and a pawl, V, which is pivoted to a sleeve, W, secured to the shaft C, communicates a quarter of a revolution to the cam S by means of the ratchet Y on the 75 cam, and the cam oscillates the lever R, so that the bar M, with which the lever engages, is moved longitudinally toward the anvil until a recess, Z, in the under surface of the bar is made to register with the upper end of the 80 rivet. Then, as the hammer descends the second time, a head is formed on the upper end of the rivet by means of the recess Z. It will thus be seen that the longitudinal movement of the bar M enables the rivet to be inserted 85 and headed by two successive blows of the hammer without separate adjustments of the parts for each step in the process.

In order that the normal position of the bar M above the anvil may be adjusted to suit rivets of different lengths, the oscillatory rod O, which carries the bar M, is provided with a wrench or rigid arm, A', which is adapted to be held against the tension of the spring U by a screw bearing against the under surface of 90 the frame A, and a nut on the screw for regulating the adjustment of the arm A'. To prevent the bar M from turning in the sleeve N, a guide-pin or feather, B', is arranged in suitable projections on the sleeve and bar, respectively. C is a rest to prevent the vertical oscillation of the lever R when it passes out of engagement with the cam S. The cam S is loosely mounted on the shaft C, and receives

an intermittent movement in a single direction as the hammer repeatedly rises and falls. D' is a retaining-pawl for the ratchet.

Fig. 5 is a modification of the end of the sliding bar M, showing two fingers, E', instead of one. The object of this construction is to adapt the bar for inserting two rivets at a single operation, as in riveting on the handle of a cup. The hammer is to fall upon the bar at the juncture of the two fingers. Fig. 6 is also a modification of the bar M, showing an upward curve, F', to adapt the same for use in riveting on the spouts of coffee-pots.

What I claim is—

- 15 1. The combination of the hammer, the shaft carrying the hammer and provided with a cam, the rivet-heading arm, and the lever arranged in engagement with the cam and arm, substantially as shown and described.
- 20 2. The combination of the hammer, the hammer-carrying shaft having a pawl-and-ratchet operated cam, and means for oscillating said shaft, the rivet-heading arm adapted to have both a longitudinal and a vertically oscillating movement, and the lever for communicating a longitudinal movement to the arm from the said cam, substantially as shown and described.
- 25 3. The combination, with the hammer and the anvil, of the rivet-heading arm consisting

of the spring-tensioned sliding bar having a 30 perforation in its end and a heading recess in its under surface, and the spring-tensioned oscillatory rod carrying the said sliding bar, and means for communicating a longitudinal movement to the sliding bar, in the manner and for 35 the purpose set forth.

4. The combination, with the rivet-heading arm adapted to have a longitudinal and a vertically oscillating movement, of an adjusting device, substantially as shown and described, 40 for holding the rivet-heading arm normally at any desired distance above the anvil, for the purpose specified.

5. The combination, with the anvil and rivet-heading arm, of the centered shaft adapted to 45 be operated by a strap against the tension of a spring, the hammer adjustably secured to the shaft, the loose cam and ratchet operated by a pawl on the shaft, and the lever connecting the cam with the rivet-heading arm, substantially as shown and described.

The above specification of my invention signed by me this 9th day of February, 1883.

J. R. CONNOR.
